UNITED STATES PATENT OFFICE.

JOHN M. MARLIN, OF NEW HAVEN, CONNECTICUT.

BALL-BEARING.

SPECIFICATION forming part of Letters Patent No. 331,899, dated December 8, 1885.

Application filed November 6, 1885. Serial No. 182,065. (No model.)

To all whom it may concern:

Be it known that I, JOHN M. MARLIN, of New Haven, in the county of New Haven and State of Connecticut, have invented a new and useful Improvement in Ball-Bearings, of which the following is a specification.

My invention relates to ball-bearings for shafts; and it consists in certain improvements in the ball-bearings shown in the Letters Patent granted to D. K. Hickok, April 24, 1866, No. 54,156, and to D. H. Rice, July 21, 1885, No. 322,482, substantially as hereinafter described and claimed.

In the drawings, Figure 1 is a side view of the ball-bearing constructed according to my improvements. Fig. 2 is a transverse section of the same upon the shaft on lines Z Z of Fig. 1.

S is the shaft, having a groove, s, made around an enlargement upon it to receive the balls, as shown. D is one member of the ball-bearing, and E is the other member, having inclined faces on their interior circumferences, which, when joined together, form a groove to receive the balls, as shown. b b are the balls held between these inclined faces and the faces of the groove s in the shaft. b' b' are the screws used to draw the parts D and E toward each other to adjust the bearing. b² is the gage-ring screwed upon the outer circumference of the part E, as shown, and against which the face of the part D abuts to regulate the distance to which the screws are to be set up, as described in the said former Letters Patent. Instead of having this gage-ring sur-

round the part D, as shown in the said patent of Rice, I merely abut it against it, and I turn an annular countersink within the part E of the bearing, and form a corresponding annular projection, d, upon the part D, which enters within the said countersink and fits the same snugly, substantially as shown in the patent of said Hickok, except that the wall of the countersink in my bearing meets the inner inclined ball-bearing face of the part E, instead of being outside of the latter. I thus retain the parts D E in transverse position, and construct a bearing which is adapted to be adjusted to different sizes of balls with greater facility than that of Hickok. I am also enabled to make the outer case of the ball-bearing by this means somewhat smaller in diameter. The part E of the bearing has a projection, e, upon it, to permit it to be attached to the frame which supports the bearing.

What I claim as new and of my invention is—

In a ball-bearing, the combination of the bearing-ring E, the gage-ring b², the bearing-ring D, constructed with the portion d, projecting within a countersink in the part E, which meets its inclined ball-bearing face, and the adjusting-screws b' b', substantially as described.

JOHN M. MARLIN.
